UNITED STATES PATENT OFFICE.

LEO EHRLICH, OF ST. LOUIS, MISSOURI.

LETTER-BOX.

SPECIFICATION forming part of Letters Patent No. 329,293, dated October 27, 1885.

Application filed September 18, 1884. Serial No. 143,402. (No model.)

To all whom it may concern:

Be it known that I, LEO EHRLICH, a citizen of the United States, residing at St. Louis, in the county of St. Louis and State of Missouri, 5 have invented certain new and useful Improvements in Letter-Boxes, of which the following is a specification, reference being had therein to the accompanying drawings.

My invention relates to certain improvements in letter-boxes, and is designed to produce a device that shall be a perfect safeguard against the fraudulent extraction of mail-matter from the box by carriers or other persons. Further, it is designed to prevent the direct 15 handling of mail-matter by the carrier.

In the description of the device reference will be made to the annexed drawings, in which Figure 1 represents a vertical section through the box, the contained mail-bag being 20 shown in full, and Fig. 2 a perspective of the box with the door opened; Fig. 3, a detail perspective of the bag, and Fig. 4 a plan view of the plate at the letter-receiving orifice of the bag.

25 A designates the body of the box, which is of the construction and form of an ordinary mail-box. The door B is preferably hinged at the bottom and secured at the top by a lock in the usual manner. This, with the usual 30 covered letter-receiving slot C, constitutes a common letter-box, but which is open to the objection that the honesty of the carrier is the only safeguard provided in the collection of the mail. To take all responsibility from the 35 said carrier a small bag, D, is provided. This bag is made of leather, canvas, or other tough and pliable material, and is of such size as to easily fit in the box, as shown. The bottom of the bag is provided with an opening similar to that on the large transportation-bags, 40 and which consists of two flaps, M N, one provided with staples P, which pass through slots in the other. The staples are secured by a strap, O, secured to one side of the bag, and 45 passing through the staples, the free end being slotted so as to receive a staple, P', on the other side of the said bag, and there be secured by a lock, R, the key of the same being at the central office.

50 It being necessary that the public should be enabled to insert the letters in the bag, one end is provided with two metal frames, E and

F, one, F, having hinged to it a series of spring-actuated doors or wings, G, the hinging being alternately at the top and bottom. 55 When the bag is not in the box, these wings are kept normally closed by springs G', arranged on their axes. Thus while the insertion of a letter is easy, the extraction is rendered impossible, the carrier in whose possession the bag is, not having time to go through the fine manipulation necessary in overcoming the obstacles this style of closing presents. The two metal plates secure between them the 60 edges of the slot in the bag. 65

The operation of the spring-retained wings is entirely automatic in closing, they being opened by the insertion of the letter, and then immediately brought to the closed position by the springs. The other and corresponding 70 end of the bag is provided with an eye, H, of leather or metal, as preferred. On the inside of the box and on each side of the slot C is a projecting strip or flange, I. These strips enter the metal-bound slot in the end of the 75 bag, and forcing the wings G apart, leave a clear passage for the letters, as is evident. This arrangement supports one side of the bag when in the box, the other being supported by a hook, K, which engages with the eye H. 80 The rounded top or water-shed A' of the box is formed into a paper-receptacle by means of a partition, S, and a hinged door, T. This door is kept normally shut by means of a spring, T', coiled around the hinge-bolt. On 85 the said door are two curved projections—one, U, for covering the hinge and protecting it from the weather, and the other, V, for the purpose of a handle in opening the said door. On the door B of the box is a projection, W, 90 that presses against the end of the frames E and F, the other end of the said frames pressing against a plate, X, correspondingly placed on the inside of the back of the box. This arrangement effectually holds the end of the 95 bag in place.

In operation each box will be numbered or otherwise designated, and have two bags of the same number or designation, one bag being left in the box while the other is carried 100 to the office.

The operation of the device is clearly apparent from the above description, and it will be seen that the various parts operate con-

junctively to produce a truly safe and perfect letter-box.

Having described the device, what I claim is—

- 5 1. The combination of a mail-box having a letter-receiving slot, on each side of which inwardly project strips, and having on its inner opposite side a hook, with a mail-bag provided with an open end normally closed by a strap 10 and suitable lock, and having at one corner of the opposite side an eye and at the other a rigid frame surrounding the letter-receiving slot of the bag, said frame being provided with spring-actuated wings pivoted therein, the 15 frame also adapted to fit over the projecting strips of the box, the several parts operating substantially as and for the purpose specified.
2. In combination with a box having a letter-receiving slot and inwardly-projecting strips or flanges on each side thereof, and having on the inner side opposite the slot a hook, a mail-bag having at one corner an eye and at the other an automatically-closing orifice adapted to coincide with the letter-receiving 25 slot in the box, substantially as and for the purpose specified.

3. The combination, with a mail-box having a letter-receiving slot, on each side of which there are inwardly-projecting strips or flanges, the said box having on the inner side, opposite the slot, an inwardly-projecting hook, of a mail-bag having an eye at one end and at the other end a frame carrying spring-actuated wings, said frame being adapted to receive the strips or flanges on the box, substantially as 35 and for the purpose specified.

4. A mail-box having a rounded top and a partition dividing the main portion of the box from the said top, and thereby forming two independent compartments, the upper compartment having one end permanently closed and the other end normally closed by a door, the two compartments forming, respectively, a paper-receptacle and a letter-receptacle, substantially as and for the purpose specified. 45

In testimony whereof I affix my signature in presence of two witnesses.

LEO EHRLICH
